DISPLAY PLATE OR SIMILAR ARTICLE

Socrates M. Mackitar, West New York, N. J.

Application September 29, 1949, Serial No. 5,211

Term of patent 14 years

(Cl. D14—6)

To all whom it may concern:

Be it known that I, Socrates M. Mackitar, a citizen of the United States, residing at West New York, Hudson County, State of New Jersey, have invented a new, original, and ornamental Design for a Display Plate or Similar Article, of which the following is a specification, reference being had to the accompanying drawing, forming a part hereof.

Figure 1 is a front elevational view of a display plate, showing my new design; and

Figure 2 is a vertical edge view of the display plate shown in Figure 1.

The essential features of the design reside in the shield portion above the connecting tab.

I claim:

The ornamental design for a display plate or similar article, substantially as shown and described.

SOCRATES M. MACKITAR.
